JOSEPH SLADKY AND ALEXANDER C. SLADKY, OF MILWAUKEE, WISCONSIN, ASSIGNORS
TO NATIONAL ENAMELING & STAMPING CO., INC., OF MILWAUKEE, WISCONSIN

TEMPERATURE ACTUATED AUTOMATIC CONTROL VALVE

Application filed October 8, 1928. Serial No. 311,229.

This invention relates to temperature actuated automatic control valves.

In gasoline stoves, it is the practice to heat the generator tube to generate the gas for the burner by any suitable means prior to allowing the fuel to pass to the burner. It sometimes happens through carelessness, or other causes, that the fuel is allowed to pass to the burner before the generator tube is sufficiently heated, with consequent flooding and sometimes with serious results.

This invention is designed to overcome the defects noted above, and objects of this invention are to provide a temperature actuated automatic control valve which is applicable to the control of gasoline stoves and to other analogous uses, and which is so made that it is necessary to heat the generator tube and an associated member before gasoline or other fuel can pass to the generator and main burner, so that there is no possible chance of flooding the burner or, in other words, allowing the fuel to pass thereto before the generator tube has been sufficiently heated.

Further objects are to provide an automatic device which functions without any thought on the part of the operator, which is relatively simple and easy to install, which is so constructed that an expandible liquid or gas, which will hereinafter be referred to as fluid, is employed to actuate a control valve for the fuel flow so that when a sufficient temperature has been obtained, the fluid will expand and actuate the control valve to permit the passage of fuel, and which will close the valve if the main burner goes out.

An embodiment of the invention is shown in the accompanying drawing in which:

The single figure is a diagrammatic view showing the device associated with a gasoline burner and with the priming cup.

It is to be distinctly understood that although this invention is described and illustrated as applied to gasoline burners primarily, that nevertheless it is of wider scope and the description and illustration are intended merely to show one embodiment there-

of. For instance, it may, obviously, be applied to gas burners.

Referring to the drawing, it will be seen that a generator tube 1 is connected by means of a pipe 2 through the automatic device, to a supply pipe 3. The other end of the generator tube is connected to the burner 4. The generator tube may be provided with a hand control, as indicated at 5, in the usual manner.

A priming cup or heating cup 6 is positioned below the generator tube and also below an expansion chamber or device 7. This expansion chamber is connected to a head 8 which is screwed into a casing 9. Between the head and casing, a diaphragm 10 is clamped. This diaphragm may be of metal, or any suitable material, and it may be otherwise sealed with respect to the casing and head, than as shown in the drawing. At all events, a gas-tight joint is formed with the diaphragm, so that there can be no loss of material from the expansion chamber or member 7.

The member 7 is provided with a cylindrical extension 11 within which a guiding plunger 12 slides. This guiding plunger is provided with a reduced extension 13 which has a valve 14. This valve may be conical, as illustrated, and may close the aperture 15, as indicated. From the valve, a rod 16 extends to a head 17 which bears against the diaphragm 10. A spring 18 urges the plunger and valve towards valve closing position, so that the valve normally contacts with the valve seat and cuts off communication between the pipes 3 and 2, the pipe 3 extending to a gasoline supply tank. It is to be noted that the diaphragm 10 also seals the device against leaking from gasoline, as it is in direct contact with the supplied fuel.

The cylindrical portion 11 of the device may be closed by means of a threaded plug 19 which cooperates with a gasket 20 to seal the end of the cylindrical casing 11. The end of the plug bears against the outer end of the spring 18.

It is to be distinctly understood that the showing is merely diagrammatic and that the position of the burner may be altered, as desired. It is shown in the position indi-

cated in the drawing merely for the sake of clearness.

The mode of operation of the apparatus is as follows:

Gasoline from any suitable source is conducted to the priming cup or heating cup 6, for instance, by means of a pipe 21. The gasoline in the cup is lighted and the flame heats the generator tube 1 in the usual manner. In addition to this, the member 7 is heated and the fluid expands and forces the diaphragm 10 to the right, as viewed in the drawing. This unseats the valve 14 and allows fuel to pass to the generator tube 1, which also has been heated from the fuel in the priming cup or heating cup 6. The exact flow of fuel required is governed by adjusting the hand wheel 5 in the usual manner.

It will be seen, therefore, that no additional act is required on the part of the operator other than that of lighting the fuel in the priming cup in the usual manner. The device functions automatically and when a certain degree of temperature has been obtained for the generator tube and, consequently, for the expansion device, the automatic valve is opened and fuel passes to the generator tube and from thence to the main burner.

It will be seen that inadvertent flooding of the burner before heating the generator tube cannot occur.

It is also to be noted that in the event that the flame from the main burner goes out, that the member 7 will immediately cool off and the fluid contained therein will contract. This will allow the automatic valve to close and cut off further supply of fuel to the burner. There is thus no possible chance of damage, even in the event that the main burner flame should become extinguished.

The expansion chamber 7 is continually heated by the main burner under normal operations, and the valve is held open. However, when the main burner is shut off, the expansion chamber 7 rapidly cools and the fluid contracts, thus allowing the valve to close.

Although the invention has been described in considerable detail, such description is intended as illustrative rather than limiting as the invention may be variously embodied and as the scope of such invention is to be determined as claimed.

We claim:

The combination with a burner, a priming cup, and a generator arranged intermediate the burner and priming cup communicating with the burner at one end, of a cylindrical casing disposed at one side of the burner and priming cup having a partition provided with a bore defining a valve seat, inlet and outlet nipples communicating with the cylindrical casing on opposite sides of the partition, means connecting the end of the gen-

erator tube opposite the end connected with the burner to the outlet nipple, a flared casing on the end of the cylindrical casing adjacent to the outlet, a diaphragm, a head clamping the diaphragm in the flared casing having a central opening, a tube having an expansible medium therein carried by the head and communicating with the opening, a valve stem slidible in the cylindrical casing through the bore having a valve thereon for the valve seat, one end of the stem engaging the diaphragm and an expansion spring confined in the cylindrical casing engaging the opposite end of the stem.

In testimony that we claim the foregoing we have hereunto set our hands at Milwaukee, in the county of Milwaukee and State of Wisconsin.

JOSEPH SLADKY.
